CONTROL DEVICE FOR ATOMIZER NOZZLES,
BURNER HEADS, AND THE LIKE

Pietro Del Genovese, Pisa, Italy

Application June 30, 1936, Serial No. 88,226
In Italy April 7, 1936

5 Claims. (Cl. 299—118)

My present invention has for its object to provide a control device for atomizer nozzles, burner heads, and the like, which controls the flow of the liquid to the ejector head through a double system of intercepting members so as to positively prevent losses of liquid from the nozzle, and also permit of instantaneously starting and stopping the action of the nozzle.

A nozzle provided with the controller according to my present invention permits of semi-automatically controlling the flow of the liquid to the ejector or atomizer head, and variating the section and number of passages leading to said head, and securing a broad range of discharge of atomizer.

My invention further comprises a device for automatically cleaning a filter and expelling, by operation, the impurities from the liquid to be atomized, by operating the discharge controller. The said expulsion of the impurities is effected by the operation, and independently from the operation of the atomizer. Thereby the necessity of dismounting the filter for cleaning purposes is avoided.

My invention is illustrated by way of example in the annexed drawings in which:

Fig. 1 is an axial longitudinal section of an atomizer nozzle comprising the control device according to invention.

Fig. 2 is a section on line II—II of Fig. 1.

Figs. 3, 4 and 5 are sections on line III—III of Fig. 1 and show the double cam and valve in three different positions, respectively,

Figs. 6, 7 and 8 are diagrams of the reciprocal positions of passages of ejector head and passages of rotary valve to be described hereafter with reference to Figs. 3, 4 and 5, and

Fig. 9 is a sectional view of a modification of part of the device shown in Fig. 1.

The nozzle, Fig. 1, comprises a hollow body 1 on the front end of which the ejector head 2 is screwed which in the example shown comprises a spherocylindrical member 3. Bearing on the back face of the ejector head 2 and the spherocylindrical member 3, a cylindrical body 4 with passages 5 continued in grooves 6 is provided on the outer side face of member 3 and converging in the front ejector chamber 7 whence the liquid is discharged through passage 8.

Bearing on the back face of the cylindrical body 5 there is a rotary valve 9 comprising a rotary body with passages 10 (see also Fig. 2) connecting chamber 11 to passages 5 of cylindrical member 4 as will be described hereafter.

Rotary valve 9 is operated by fly wheel 12

through shaft 13 on which cam 14 is keyed. The latter operates valve 15 through spindle 16. The pressure of liquid acting on the back face of rotary valve 9 is counter-balanced by the pressure acting on the front face of rotary body 17, and a sufficiently tight closure between the shaft 13 and the back part 19 of body 1 is effected by the packing 18.

The control device operates as follows:

In the position of rest the nozzle and the parts are in the positions shown in Figs. 3 and 6. The cone valve 15 bears on its seat 15', and the truncated cone valve 20 bears on its seat 21. It is, however, to be noted that the latter may be omitted in certain modifications of my present invention, as is seen for instance in Fig. 9. Cam 14 bears with its part of minimum radius 22 against tip 23 of spindle 16. The liquid under pressure from the feeding duct through nipple 24 is opposed by said valve 15, and therefore no appreciable pressure acts on rotary valve 9, Fig. 1. In this position the passages 10 of valve 9 are in correspondence with passages 5 of member 4, as is shown in the diagram of Fig. 6.

In Fig. 4 cam 14 has effected a rotation of about 45° in the direction of the arrows, and raised stem 16 of valve 15 up to such position that the truncated cone valve 20 has been raised by flange 25 of stem 16. In this position between the truncated cone valve 20 and its seat 21 a narrow path is opened through which the flow of liquid to chamber 11 of burner 1 is partially choked. At the same time the rotary valve 9 is in the position shown in Fig. 7 with respect to passages 5 of member 4. Cam 14, which is here shown double for illustrative purposes is provided with notches 14' co-operating in known manner with tip 23 of stem 16.

Fig. 5 shows valve 20 raised completely from its seat, cam 14 being turned by about 90° from the position shown in Fig. 3. In Fig. 8 passages 10 of rotary valve 9 are shown in front of passages 5 of member 4.

As is seen from Figs. 6, 7 and 8, passages 10 are preferably,—though not necessarily,—of elliptic section with the greater axis placed perpendicularly to the radius passing through the centre of the canal. Owing to this conformation of passages 10, canals 5 being of circular section, the choking of flow of liquid from passages 10 to passages 5 during operation of flywheel 12 is gradual and a little in advance and retard, respectively, of movements of valves 20 and 15.

Back part 19 of body 1 of burner instead of

55 55

being integral as shown in Fig. 1, may also be separable, such as shown at 19' in Fig. 9.

26 is a pointer co-operating with a disc 27, and indicates to operator the relative position 5 of cam 14 to valves 9, 15 and 20.

In chamber 11 is placed a truncated cone filter 28 rotatable with shaft 13 co-operating with fixed preferably elastic scrapers 29 designed for detaching residues left on filter 28 and collecting 10 same in the funnel formed from whence they are discharged from time to time through a cock 31. On the other hand, of course, the filter 28 may be fixed and, vice versa, the scrapers 29 controlled by the rod of flywheel 12 may be 15 rotatable. In order to fix the position of flywheel 12 any suitable known device may be used, such as for instance, a pawl co-operating with a ratchet wheel, or the like.

It is understood that my invention has been 20 described and illustrated by a preferred form of realization but structural modifications may be made within the scope of the invention.

Having now particularly described and ascertained the nature of my said invention and in 25 what manner the same is to be performed, I declare that what I claim is:

1. A control device for a fuel burner nozzle comprising a rotary valve having a plurality of discharge openings, said valve being rotatable to 30 selectively open different numbers of said openings for controlling the flow of fuel to the nozzle, a rotatable shaft for operating said valve, a second valve having a stem controlling the flow of fuel to said rotary valve and cam means upon 35 said rotatable shaft acting on said stem for operating said second valve in synchronism with said first mentioned valve to open said second valve more or less respectively as a greater or less number of openings in said rotary valve are opened 40 to thereby correlate the fuel supplied by said second valve to the fuel discharged by said rotary valve.

2. A control device for a fuel burner nozzle comprising a rotary valve having a plurality of discharge openings, said valve being rotatable to 45 selectively open different numbers of said openings for controlling the flow of fuel to the nozzle, a rotatable shaft for operating said valve, a second valve controlling the flow of fuel to said 50 rotary valve constantly urged to closed position by the pressure of the fuel, a stem upon said second valve and cam means upon said rotatable shaft for acting on said stem to open said second valve against said fuel pressure whereby said 55 second valve is operated in synchronism with said first mentioned valve to open said second valve more or less respectively as a greater or less number of openings in said rotary valve are

opened to thereby correlate the fuel supplied by said second valve to the fuel discharged by said rotary valve.

3. A control device for a fuel burner nozzle comprising a rotary valve having a plurality of 5 discharge openings, said valve being rotatable to selectively open different numbers of said openings for controlling the flow of fuel to the nozzle, a rotatable shaft for operating said valve, a second reciprocating valve controlling the flow 10 of fuel to said rotary valve and a cam fixed to said rotatable shaft acting directly upon said reciprocating valve for operating said reciprocating valve in synchronism with said rotary valve to open said second valve more or less respectively as a greater or less number of openings 15 in said rotary valve are opened to thereby correlate the fuel supplied by said second valve to the fuel discharged by said rotary valve.

4. A control device for a fuel burner nozzle 20 comprising a rotary valve having a plurality of discharge openings, said valve being rotatable to selectively open different numbers of said openings for controlling the flow of fuel to the nozzle, a rotatable shaft for operating said valve, 25 a second reciprocating valve having a stem controlling the flow of fuel to said rotary valve, a delayed action valve cooperating with said reciprocating valve also controlling the flow of fuel to said rotary valve and cam means upon said 30 rotatable shaft acting upon said stem for operating said reciprocating valve and said delayed action valve in synchronism with said rotary valve to open said second valve more or less respectively as a greater or less number of openings 35 in said rotary valve are opened to thereby correlate the fuel supplied by said second valve to the fuel discharged by said rotary valve.

5. A control device for a fuel burner nozzle comprising a rotary valve having a plurality of 40 discharge openings, said valve being rotatable to selectively open different numbers of said openings for controlling the flow of fuel to the nozzle, a rotatable shaft for operating said valve, a second valve having a stem controlling the flow of 45 fuel to said rotary valve, cam means upon said rotatable shaft acting on said stem for operating said second valve in synchronism with said rotary valve to open said second valve more or less respectively as a greater or less number of openings in said rotary valve are opened to thereby correlate the fuel supplied by said second valve to the fuel discharged by said rotary valve and notches upon said cam means cooperating with said stem for determining predetermined openings of said second valve.

PIETRO DEL GENOVESE.
